WELL TESTING DEVICE

Thomas Noah Smith, San Antonio, Tex.

Application November 2, 1937, Serial No. 172,431

6 Claims. (Cl. 166—1)

This invention relates to well testers for use in testing a well preferably of the gas and oil type, to determine whether a producing stratum has been reached.

Up until recently, the commonly accepted method used for testing wells involved considerable labor and expense and quite frequently resulted in destroying the well. It generally involved the setting of well casing and a screen together with the work of cementing the well before the test could be made. The well then had to be washed and tested and if it was found that no producing formation had been reached, the liner, screen, wash pipe and related equipment had to be removed, so that the well could be drilled further into another stratum. Seldom, if ever, was the screen recovered in a condition where it could be used again because of the fact that it had been so firmly anchored.

It is an object of this invention to provide a device which can be quickly introduced into the well to make a test of the formation and then again easily withdrawn, all with a minimum expenditure of time and money.

A particular object of the invention is to provide means whereby the tool may be seated in the bore hole and packed off before the valve is opened, so that a proper seat is assured and the fluid below the packer is shut off before the valve is opened.

Still another object of the invention is to provide valved means above the packer for setting up a circulation of flushing fluid down through the string of pipe and up the outside thereof, equalizing pressures and thereby causing a back pressure to force the liquid or gas back in order to prevent a blow out, a very serious but not common happening when testing wells at different strata.

Yet another object is to provide a novel form and construction for the packer employed.

A further object of the invention is to provide a valve means provided with fluid ducts, so designed that the fluid issuing therefrom under high pressure and containing particles of foreign matter will not have a tendency to erode the valve seat.

A still further object of the invention is to provide a testing tool in which the parts are so designed and arranged as to make for ease in assembly, economy in the cost of manufacture and simplicity and efficiency in operation.

Referring to the drawings:

Fig. 1 is a central longitudinal section through the device embodying the invention;

Fig. 2 is a central longitudinal section through the device, showing the same in a seated position in a formation to be tested;

Fig. 3 is a fragmentary view showing the jawed members at the zone where the packer body and the drill stem meet, in the position at the time the device is being lowered into the well;

Fig. 4 is a fragmentary view at the same zone of the same parts, in the position where the packer body is seated, in the formation;

Fig. 5 is a fragmentary vertical section showing a modification of the packer in a position before seating;

Fig. 6 is a fragmentary vertical section of the modification shown in Fig. 5 but in the position after seating;

Fig. 7 is a perspective view, partly in section, showing the packer removed from the device; and

Fig. 8 is a modification of the valve means shown in Figs. 1 and 2.

This tool is intended for use in the rotary system of drilling wells, wherein the work of producing a hole is done by a bit attached to the end of a tubular drill stem. The drill stem is rotated by a rotary, the connections between the drill stem and the rotary being such that the drill stem may be fed downwardly while, at the same time, it is being rotated. Simultaneously with the rotary and downward motion of the bit, drilling fluid, or mud, is pumped downwardly through the drill stem, this fluid emerging from ports, or water courses, in the bit. After the drilling fluid leaves the bit it travels upwardly through the space between the drill stem and the well wall to the surface, where it is stored in a "slush pit" for use again. This drilling fluid serves to cool the cutting edges of the bit; to remove cuttings made by the bit; and to prevent, so far as possible, "blowouts" which might occur when high pressure formations are encountered.

Since the well is full of this drilling fluid at all times, it is clear that the static pressure at any given point in the well is dependent upon the head of the fluid above that point. Usually, therefore, in deep well drilling the static pressure in the well is sufficient to prevent blowouts.

But the static pressure also has its objections. One of them is that oil or gas bearing strata might be passed without the driller having knowledge of this. This is because the static pressure of the drilling fluid serves to prevent the entrance of gas or oil into the hole unless the gas or oil is under sufficient pressure to enter the well against the static pressure.

In order to eliminate the possibility of passing

producing formations during the drilling of the well, it is customary to take frequent tests when in the vicinity of producing strata. This is done by running a bit of smaller diameter than the 5 regular drilling bit, forming a hole of reduced diameter through the strata to be tested. The smaller hole is known to the operator as a rat hole, and the shoulder of this hole furnishes a sealing means for sealing off the static pressure 10 of the well from the rat hole while the device rests on the shoulder and the test is being made. Upon the shoulder casting may also be set, should production be discovered in the small rat hole. The rat hole is usually cored in by one crew 15 of workmen. The next crew reams down, leaving a full-gauged hole to bottom, ready for the next crew to begin rat-holing or core drilling again. The core obtained in the rat hole operation gives the driller an accurate log of the well 20 and also gives him an indication of when oil or gas formation is reached.

After drilling the rat hole the entire string of drill stem is removed from the well and the bit is replaced by the testing tool. The bit is removed from the hole during testing. The valve 25 of the testing tool is held in a closed position during the time the tool is being lowered; consequently the inside of the drill stem contains no fluid and for this reason there is no static pressure 30 in the drill stem. In other words, the well is full of drilling fluid but there is none in the drill stem.

After the testing tool has been seated on the shoulder of the rat hole and the static pressure 35 from the hole above has been sealed off from the rat hole, the valve in the testing tool is opened thereby relieving the formation being tested of all static pressure. Any oil or gas in the strata being tested will now enter the rat hole, pass 40 through the valve of the testing tool and into the drill stem, thus furnishing a sample of the producing capacity of that particular strata.

On removing the tool from its seat the valve is again closed, thereby retaining the fluid which 45 has entered during the test, until the tool is raised to the surface.

The device of Fig. 1 is intended to be secured to the lower end of a hollow drill stem 1 by means of the threads shown or a standard A. P. I. drill 50 stem tool joint or coupling (not shown), and inserted downwardly into the well within the casing 2. The hollow drill stem serves to control and operate the testing device. The nipple or short length section 3 constituting a sample retaining 55 chamber, has formed therein a flared mouth 4 and is formed with screw threads 5 to which is adapted to be secured the valve housing 6, said housing having a valve seat 7 upon which is adapted to seat a valve 8.

60 The valve is housed, as shown, the valve stem 9 having a sliding fit therewith and being provided throughout its lower extremity with threads 10, securing the packer body proper 11 to the valve housing 6.

65 The valve housing is provided with a downwardly depending guide 15, adapted to fit within and slide with respect to a guide 16 formed on the packer body proper.

A helical spring 17, of the proper tension, is 70 placed within the recess formed by the guide 15 and surrounds the valve stem 9, as shown, said spring aiding in keeping the parts 6 and 11 apart while the device is being lowered into the valve.

The valve stem has a longitudinal bore 20 there- 75 in, extending throughout its length, said bore

communicating with a plurality of horizontal openings 21, which openings lead to a recess 22 formed in the valve housing and directly below the valve seat 7 and valve 8.

The lower portion of the bore 20 has screwed 5 therein a choke plug 25 which is provided with passage 26, said passage in turn communicating with passages or fluid inlet openings 27 and 28 in the bull plug or strainer 30, which depends from the valve stem 9 and is separated from the 10 packer body proper by lock washer 31.

The packer body proper 11 is shaped as shown, provision being made for a plurality of superimposed layers of packing material 35, suitably secured to the packer body by any well known 15 means. The packing material is made of rubberized material or of leather belting. One of the features of the packer body is that, due to the square shoulder 36, it can easily be seated on soft or hard formations, without forcing said forma- 20 tions outwardly. The shoulders 36 seat on the shoulders 37 of the rat hole 38. Frictional resist- 25 ance between the packing material and the forma- tion seat will prevent rotation of the packer body.

Turning now to Fig. 1, and particularly to the 25 portion marked A, one views the tool in which the relative positions of the cams, spring and valve when entering or leaving the well, are shown. Fig. 3 should also be considered in connection with Fig. 1, since this shows the cam arrangement at 30 the portion marked A. In Figs. 1 and 3, the cam arrangement or jaws are shown in a closed position. The jaws, dogs, or cams 40 and 41, there being a plurality of them around the circumference of the valve housing and the packer body, 35 are shaped as shown in Fig. 3. The spring 17 is a compression spring and is employed to aid the packer body and valve housing to separate when the jaws or cams are rotated to the proper point, and it is also employed to hold the jawed mem- 40 bers apart when the testing device is raised from its seat after the test is completed, thereby clos- 45 ing the valve 8 against the static pressure of the well and preventing the entrance of drilling fluid into the drill stem. In Fig. 1, the static pressure 45 in the well acts against the area of the valve 8 which, except for the force exerted by the spring 17, would cause the valve 8 to open. Drilling fluid would then enter the drill stem and ruin any test that has been taken. In removing tests 50 of very deep wells where the force exerted by the spring 17 is not great enough to hold the valve 8 against its seat 7, the drill stem may be rotated to a partial turn before raising the packer off of its seat, bringing the raised portions of the jaws 55 or cams in line and closing the valve 8. The relative positions of the parts while making the test are shown in Figs. 2 and 4 and the jaws or cams 40 and 41 are as shown at the portion B of Fig. 2.

After the testing tool has been seated on the 60 shoulder of the rat hole and the static pressure from the hole above has been sealed off from the rat hole, the valve 8 is opened by rotating part 6 clockwise with respect to part 11, so that the jaws or cams take the position shown in Fig. 4, 65 thereby relieving the formation being tested of all static pressure. Any oil or gas being tested will enter the rat hole, pass through the stem of valve 8 and into the drill stem, above valve 8, thus furnishing a sample of the producing ca- 70 pacity of the well.

The direction of rotation of the drill stem for the opening and closing operations of the valve is always clockwise or in the same direction. This is important, since the joints composing 75

the drill stem are joined together with right hand threads. Any rotation in the reverse direction might cause the threads and joints to loosen.

The reason the square shoulder of the packer is provided, is manifest. When the packer is seated on the shoulder of the rat hole, the entire weight of the drill stem is allowed to rest on the packer. If an angular form of packer is employed, as is common in the art, this great weight causes the packer to be wedged into the rat hole so tightly that it is very difficult to remove the packer. The wedging action is eliminated by using a square shouldered packer.

In the modification shown in Fig. 7, the packer body is designated as 55 and is composed of a metal supporting member surrounded by a rubber composition member 56, shaped as shown. Any desired fibrous composition might be used instead of the rubber composition, to suit individual conditions. As shown, the lower end of the packer is slightly cupped, so that when it is seated on the upper edge 37 of the rat hole 38, the edge 58 will turn outward and thereby aid materially in securing a perfect seal. This condition is best shown in Fig. 6. It will be noticed that the metal supporting member 55 is provided with an annular flange 59, having an annular row of spaced perforations 60 and that the annular flange 59 is located nearer to the upper portion of the member 55 than it is to the lower portion thereof. This assures greater resiliency to the material 56 below the flange 59. The material 56 encompasses the flange 59 and is also worked into the perforations 60. Another object in locating the flange 59 as shown, is that, in removing the packer from its seat, the pull of the flange 59 will tend to elongate the member 56 and thereby reduce its diameter. It is clear that this action will aid greatly the removal of the packer from its seat. Obviously, the packer here shown will not wedge in the upper end of the rat hole, and even though in some of the softer formations the packer should sink below the surface of the rat hole, and have a tendency to stick, the pull applied to the packer in removing it from the seat will cause the same to elongate and reduce the diameter thereof, thereby releasing the packer from the hole. The member 55 is held to the valve stem 9 and the threads 10 by means of the nut 57.

In the modification of the valve member, shown in Fig. 8, passages 65 near the upper end of the valve stem 9, and just under the valve 8, are provided. These passages are upwardly and outwardly directed and communicate with the bore 20. The object in providing these passages is to prevent the fluid which enters the testing device when the valve is open, from cutting across the face of the valve or the valve seat 7. This fluid, which generally enters the tool under high pressure and contains bits of sand and foreign matter, will rapidly cut any valve or valve seat with which it comes in contact. The passages 65 will guide the fluid past the valve without any cutting action.

While the test is being made and fluid is entering into the drill stem, if there should be any tendency for the pressure from the formation, either fluid or gas, to raise the drilling fluid (or mud) or get beyond control, with this device it is only necessary to start the mud pumps at the surface and apply pressure through the column of drilling fluid inside the drill stem which in turn will cause valve 50 to open, equalizing the pressures on both the column of fluid

inside of the drill stem and on the outside of the drill stem, causing a back pressure and forcing the fluid or gas back into the well, to prevent what is known as a blowout.

Other advantages, besides those mentioned, of the construction, will be apparent to those skilled in the art.

I claim:

1. In a device of the character described including a drill stem, a nipple constituting a sample retaining chamber, a valve housing secured to said nipple, a valve at the upper end of said valve housing and having a downwardly depending valve stem to which is secured a packer, said packer being slidable with respect to said valve housing, said packer and housing being provided with cooperating cammed surfaces whereby said valve can be moved away from its coating valve seat when said drill stem is rotated in one direction only with respect to said packer. 10 15 20

2. In a device of the character described including a drill stem, a nipple constituting a sample retaining chamber, a valve housing secured to said nipple, a valve at the upper end of said valve housing and having a downwardly depending valve stem to which is secured a packer, said packer being slidable with respect to said valve housing, a spring surrounding said valve stem and normally urging said valve housing and said packer away from each other, said packer and housing being provided with cooperating cammed surfaces whereby said valve can be moved away from its coating valve seat when said drill stem is rotated in one direction only with respect to said packer. 25 30 35

3. In a device of the character described including a drill stem, a nipple constituting a sample retaining chamber, a valve housing secured to said nipple, a valve at the upper end of said valve housing and having a downwardly depending hollow valve stem to which is secured a packer, said packer being slidable with respect to said valve housing, said packer being provided with cammed surfaces contacting cammed surfaces on said valve housing, a spring surrounding said valve stem and normally urging said valve housing and said packer away from each other, said valve being adapted to move to its seat when said cammed surfaces are disengaged and from its seat when said cammed surfaces are engaged and when said drill stem is rotated in one direction only with respect to said packer, whereby fluid is allowed to enter the lower end of said hollow valve stem and pass above said valve. 40 45 50 55

4. In a device of the character described including a drill stem, a nipple constituting a sample retaining chamber, a valve housing secured to said nipple, a valve at the upper end of said valve housing and having a downwardly depending hollow valve stem to which is secured a packer, said packer being slidable with respect to said valve housing, said packer being provided with cammed surfaces contacting cammed surfaces on said valve housing, said packer being provided with square shoulders for engaging the upper portion of a rat hole in a well, said valve stem having a perforated lug screwed on the lower end thereof and engaging said packer and adapted to project down into the rat hole, a spring surrounding said valve stem and normally urging said valve housing and said packer away from each other, said valve being adapted to move to its seat when said cammed surfaces are disengaged and from its seat when said cammed surfaces are engaged and when said drill stem is ro- 60 65 70 75

tated in one direction only with respect to said packer, whereby fluid is allowed to enter the lower end of said hollow valve stem and pass above said valve.

5 5. In a device of the character described for testing formations in oil wells, in which the well is provided with the usual bore and rat hole, a substantially cylindrical compressible packer mounted on a packer body secured to the valve stem of said device, said packer having substantial depth lengthwise of said valve stem and having a diameter greater than said rat hole and less than said bore hole, the lower face of said packer being cupped so that when said device is lowered into said well for testing and said compress-

ible packer rests on said rat hole, said cupped face will effect a tight seal with the formation adjacent said rat hole.

6. For use in a device of the character described, a compressible packer consisting of a 5 cylindrical rubber plug having a longitudinal bore therethrough, said bore accommodating a metal hollow tubular supporting member, which member has projecting therefrom at right angles an annular flange of substantial width, said flange 10 being provided with a plurality of through openings, said flange, openings and tubular member being embedded in said cylindrical plug, the lower face of said compressible packer being cupped.

THOMAS NOAH SMITH. 15
